(57) **CLAIM**

The ornamental design for a scroll wheel adapter for a tablet computer, as shown and described.

DESCRIPTION

FIG. 1 is a reduced perspective view of a scroll wheel adapter mounted on a tablet computer;

FIG. 2 is a top, front, left side perspective view of the scroll wheel adapter for a tablet computer showing my new design;

FIG. 3 is a left side elevation view thereof;

FIG. 4 is a front elevation view, the rear elevation view is the mirror image thereof;

FIG. 5 is a right side elevation view thereof;

FIG. 6 is a top plan view thereof; and,

FIG. 7 is a bottom plan view thereof.

The broken line showing of the tablet computer in FIG. 7 is included for the purpose of illustrating the environment of the claimed design and forms no part thereof.

1 Claim, 4 Drawing Sheets
